SNAKE ATTACHMENT

James J. Devine, 209 Clifton Ave.,
Kingston, N.Y. 12401
Filed Dec. 15, 1965, Ser. No. 514,152
10 Claims. (Cl. 15—104.3)

This invention relates to snake attachments and more particularly to a snake attachment to be slidably mounted on a flexible snake and detachably coupled to a waste line so that a flexible conduit may be coupled to the attachment to supply water to the waste line while maintaining a water-tight seal between the snake and the attachment.

Attachments generally employed for use with flexible snakes for cleaning waste lines do not provide a means for maintaining a supply of water in the waste line to be cleaned. Attachments of this type, if utilized, do not maintain the proper water-tight seal so that water does not pass through the attachment and spill onto the floor. Devices are employed so as to enable one to turn the snake so that a whipping action takes place while the snake is rotated. Various designs of snakes are available having improved devices for attachment to the end thereof so as to facilitate cleaning of a waste line. However, these devices are not generally suitable where foreign material clogging a waste line must be flushed out so as to enable the snake to completely clean the interior thereof. The pipe is generally flushed after the snake is removed and often the material loosened will again clog the line thus necessitating further work to free the material clogging the line.

It is an object of my invention to provide a simple device which is easily adapted for attachment to existing flexible snakes and existing waste lines so that water pressure may be applied to a clogged waste line to facilitate cleaning thereof.

Another object of my invention is to provide a device which is rather simple and inexpensive to manufacture, and is quickly and easily assembled and disassembled.

In general the snake attachment comprises a housing having an end plate mounted at one end thereof. The end plate is provided with an opening which communicates with a longitudinal passage formed by an assembly of a plurality of bearing members disposed within the housing. Means for providing a sealing fluid is mounted on the housing so that when a flexible snake is disposed therein the sealing fluid will fill the longitudinal passage and the interior of the housing to provide a water-tight seal. A coupling is mounted at the other end of the housing which is provided with a mounting means for attaching a flexible conduit to a water source so that water may be supplied to the waste line when the snake attachment is coupled thereto.

Other objects and advantages of my improved snake attachment will become apparent from the following description of the drawings exemplifying preferred embodiments of my invention, in which:

FIG. 1 is a side elevational view in cross-section embodying my invention showing a preferred form of assembly thereof;

FIG. 2 is a side elevational view in cross-section showing another form of assembly for effecting a water-tight seal; and

FIG. 3 is a cross-sectional view in the direction of the arrows 3—3 of FIG. 2.

Referring now to the drawings and more particularly to FIG. 1, my improved snake attachment is generally shown at 10. A housing 12, generally cylindrical in form, is provided with threaded ends 13 and 14 and end plate 16 is threadedly coupled to housing 12 on threaded end 13. A plurality of bearing assemblies 18, 19 and 20 are slidably mounted within housing 12 in spaced relation to

2

each other so that bearings 18 and 20 are disposed adjacent the ends of housing 12 and bearing 19 is disposed therebetween, as seen in FIG. 1. Openings 18', 19' and 20' are substantially equal to the opening 22 formed in end plate 16 and are coaxially aligned therewith. Spacers 24 are interposed between bearings 18, 19 and 20 so as to substantially fill the spaces therebetween. A grease fitting 15 having a threaded end 17 is threadedly coupled in threaded opening 17' of housing 12 so that sealing fluid F will pass through a central opening thereof, not shown, to fill the interior of housing 12. Openings 24' of spacers 24 are substantially greater than the diameter of flexible snake S and openings 18', 19', 20' and 22 so that recesses are formed between bearings 18, 19 and 20. When sealing fluid F is disposed within housing 12 the recesses will be filled therewith to effect a water-tight seal between the external surface of snake S and the longitudinal passage formed by openings 18', 19', 20', 22 and 24'.

A coupling 26 having a threaded opening 27 is coupled to housing 12 on threaded end 14 thereof. Coupling 26 is provided with a threaded opening 28 for coupling one end of a flexible conduit C thereto so that the other end thereof may be connected to a water source, not shown.

When snake attachment 10 is connected to a waste pipe, not shown, by threads 30 of coupling 26, water pressure may be supplied to the waste line simultaneously while snake S is passing therethrough. Thus, when snake S is being fed into the waste pipe and the material clogging the pipe is loosened it will be flushed through the pipe and into the sewer.

End plate 16 may be provided with an annular groove 32 so that a fluid tight seal 34 may be disposed therein and which will contact the surface of snake S to provide an auxiliary water-tight seal. Bearing 18 may be mounted in fixed position at one end of housing 12 as by spot welding or brazing or it may be held in fixed position by providing an auxiliary coupling 36 having an annular surface 37 so that bearing 18 will bias against the surface 38.

In FIGS. 2 and 3 an alternate embodiment is shown which provides a housing 40 having an end plate 42 coupled to housing 40 at threaded end 43. Opening 44 is provided in end plate 42 so that snake S may pass therethrough. A pair of semi-cylindrical bearing members 46 are slidably mounted within housing 40 and are provided with an annular groove 48 having spaced recesses 50 disposed therein. Transverse bores 52 are disposed in semi-cylindrical bearing members 46 so as to communicate with recesses 50. Resilient spring members 54 are disposed between the interior surface of housing 40 and the external surface of semi-cylindrical bearing members 46 so as to yieldingly hold semi-cylindrical bearing members 46 in fixed position. A grease fitting 56 is coupled to housing 40 in threaded opening 58 so that sealing fluid may pass through a central opening in fitting 56, not shown, to fill the interior portion of housing 40 and recesses 50 through bore openings 52 thereby effecting a water-tight seal between the external surfaces of snake S and the longitudinal passage 48.

A threaded coupling 60 is connected to threaded end 62 of housing 40 so as to hold semi-cylindrical bearing members 46 in fixed position and to prevent longitudinal movement thereof. End plate 42 and coupling 60 may be formed with recesses 64 and 66 so that a flexible water-tight seal 68 may be disposed therein to provide an auxiliary water-tight seal between external surfaces of snake S and longitudinal passage 48. The semi-cylindrical bearing members may be made of any convenient material, such as wood, metal casting or molded from plastic. Housings 12 and 40 may be formed of a rigid material, such as iron, steel, galvanized steel, brass or rigid plastic.

When employing my improved snake attachment, all that is necessary is to pass a flexible snake S through the longitudinally extending passage formed by the bearing members disposed within the housing. The snake attachment together with the flexible snake is threadedly coupled to a waste pipe opening and a flexible conduit C, such as a hose, is connected to the snake assembly and a water source. The water is then turned on so as to fill the clogged waste pipe. The pressure of the water is such that it will not penetrate through the water-tight seal formed by the sealing fluid such as a heavy grease for water pumps, nor through the auxiliary seals disposed within the end plates of the attachment. The snake is passed into the waste pipe and rotated in the usual manner so as to break up any material that is clogging the waste pipe. Once the snake has penetrated the material clogging the pipe, the material will be flushed into the main sewer and the pipe will be substantially clean since the whipping action of the snake continues to remove any remaining material adhering to the inner surface of the pipe.

It is obvious that many changes may be made in the design and structure of my device and various materials may be used for forming my snake assembly without departing from the spirit and scope of my invention as defined in the appended claims.

I claim:

1. A snake attachment adapted to be mounted to waste lines comprising a housing and an end plate mounted at one end thereof and having a central opening disposed therein, a plurality of washers and ball bearing assemblies slidably mounted in spaced relationship within said housing and having central openings formed therein so as to form a longitudinally extending passage communicating with said opening in said end plate, means mounted on said housing for providing a sealing fluid to fill said housing and said longitudinal passage, said openings in said ball bearing assemblies being substantially equal to the diameter of the snake so as to support the external surfaces thereof at random points through said housing and said openings in said washers being at least greater than the diameter of said snake so as to form recesses for the sealing fluid whereby water is prevented from passing through said attachment and a coupling mounted to the other end of said housing having mounting means to connect the coupling to the waste line and for attaching a flexible conduit to a water source.

2. A snake attachment as defined in claim 1 wherein said end plate is provided with an annular recess for removably mounting a water-tight seal so that when a snake passes through the opening in said end plate the water-tight seal communicates with the external surface of the snake.

3. A snake attachment adapted to be mounted to waste lines comprising a housing and an end plate mounted at one end thereof and having an opening disposed therein, a pair of semi-cylindrical members removably mounted within said housing, each of said members having an annular groove and spaced recesses formed along the longitudinal axis thereof so that when the members are placed in contact with each other a longitudinal central passage is formed, said semi-cylindrical members having transverse bores extending between the external surface of said members and recesses formed in said longitudinal passage so that sealing fluid will pass through said bores and fill said recesses whereby a water-tight seal is formed around a flexible snake when slidably mounted in said longitudinal passage and a coupling mounted to the other end of said housing and having means to connect the coupling to the waste line and for attaching a flexible conduit to a water source.

4. A snake attachment as defined in claim 3 wherein a plurality of resilient spring members are disposed between said housing and external surfaces of said semi-

cylindrical members so as to yieldingly hold said members in fixed position.

5. A snake attachment as defined in claim 3 wherein said end plate and said coupling are formed with an annular recess for removably mounting a water-tight seal so that when a flexible snake is slidably disposed in said longitudinal passage the water-tight seals communicate with the external surface of the snake.

6. A snake attachment adapted to be mounted to waste lines comprising a housing and an end plate mounted at one end thereof and having an opening disposed therein, said end plate having an annular recess for removably mounting a water-tight seal so that when a flexible snake passes through the opening in said end plate the water-tight seal communicates with the external surface of the snake, a plurality of bearing members having openings therein so as to communicate with the opening of said end plate to form a longitudinal passage through said housing, means mounted on said housing for providing a sealing fluid to fill said housing and said longitudinal passage, a coupling mounted to the other end of said housing having mounting means to connect the coupling to the waste line and for attaching a flexible conduit to a water source so that when a flexible snake is slidably disposed in said longitudinal passage the sealing fluid forms a water-tight seal between the surfaces defining the longitudinal passage and the external surface of the snake whereby water is prevented from passing through the attachment.

7. A snake attachment adapted to be mounted to waste lines comprising a housing and an end plate mounted at one end thereof and having an opening disposed therein, a plurality of ball bearing assemblies mounted in spaced relationship within said housing, a plurality of washers mounted between said ball bearing assemblies so as to form a longitudinally extending passage communicating with the opening in said end plate, means mounted on said housing for providing a sealing fluid to fill said housing and said longitudinal passage, said ball bearing assemblies having openings substantially equal to the diameter of the snake so as to support the external surfaces thereof at random points through said housing, said washers having openings at least greater than the diameter of said snake so as to form recesses for the sealing fluid, a coupling mounted to the other end of said housing having mounting means to connect the coupling to the waste line and for attaching a flexible conduit to a water source so that when a flexible snake is slidably disposed in said longitudinal passage the sealing fluid forms a water-tight seal between the surfaces defining the longitudinal passage and the external surface of the snake whereby water is prevented from passing through the attachment.

8. A snake attachment adapted to be mounted to waste lines comprising a housing and an end plate mounted at one end thereof and having an opening disposed therein, a pair of semi-cylindrical members each having an annular groove and spaced recesses formed along the longitudinal axis thereof so that when the members are placed in contact with each other a longitudinal central passage is formed, said cylindrical members having transverse bores extending between the external surface of the semi-cylindrical members and recesses formed in said longitudinal passage, means mounted on said housing for providing a sealing fluid to fill said housing and said longitudinal passage so that sealing fluid will pass through said bores and fill said recesses, a coupling mounted to the other end of said housing having mounting means to connect the coupling to the waste line and for attaching a flexible conduit to a water source so that when a flexible snake is slidably disposed in said longitudinal passage the sealing fluid forms a water-tight seal between the surfaces defining the longitudinal passage and the external surface of the snake whereby water is prevented from passing through the attachment.

9. A snake attachment adapted to be mounted to waste lines comprising a housing and an end plate mounted at one end thereof and having an opening disposed therein, a pair of semi-cylindrical members each having an annular groove and spaced recesses formed along the longitudinal axis thereof so that when the members are placed in contact with each other a longitudinal central passage is formed, a plurality of resilient spring members disposed between said housing and external surfaces of said semi-cylindrical members so as to yieldingly hold said members in fixed position, said cylindrical members having transverse bores extending between the external surface of the semi-cylindrical members and recesses formed in said longitudinal passage, means mounted on said housing for providing a sealing fluid to fill said housing and said longitudinal passage so that sealing fluid will pass through said bores and fill said recesses, a coupling mounted to the other end of said housing having mounting means to connect the coupling to the waste line for attaching a flexible conduit to a water source so that when a flexible snake is slidably disposed in said longitudinal passage the sealing fluid forms a water-tight seal between the surfaces defining the longitudinal passage and the external surface of the snake whereby water is prevented from passing through the attachment.

10. A snake attachment adapted to be mounted to waste lines comprising a housing and an end plate mounted at one end thereof and having an opening dis-

posed therein, a plurality of bearing members having openings therein so as to communicate with the opening of said end plate to form a longitudinal passage through said housing, means mounted on said housing for providing a sealing fluid to fill said housing and said longitudinal passage, a coupling mounted to the other end of said housing having mounting means to connect the coupling to the waste line and for attaching a flexible conduit to a water source, said end plate and said coupling being formed with an annular recess for removably mounting a water-tight seal, said water-tight seal communicating with the external surfaces of a snake so that when the flexible snake is slidably disposed in said longitudinal passage the sealing fluid forms a water-tight seal between the surfaces defining the longitudinal passage and the external surface of the snake whereby water is prevented from passing through the attachment.
